UNITED STATES PATENT OFFICE.

LOUIE DUCEY, OF NEW YORK, N. Y.

STOCKING-PROTECTOR.

No. 887,384.

Specification of Letters Patent. Patented May 12, 1908.

Application filed March 29, 1907. Serial No. 365,260.

To all whom it may concern:

Be it known that I, LOUIE DUCEY, a citizen of the United States, residing at the city of New York, in the county of New York and State of New York, have invented certain new and useful Improvements in Stocking-Protectors, of which the following is a full, clear, and exact description.

My invention relates to a protecting means for ladies' stockings by which they are conveniently engaged to the fastener or supporting device of any ordinary construction of garter, without any liability of tearing or injuring the fabric of the stocking.

Ladies' stockings are frequently made of silk or delicate fabric which is liable to become torn or injured if directly engaged by the mechanical gripping devices of a garter or supporter. Attempts have been made to overcome this difficulty by various special forms of gripping devices on the garter, but with only partial success. The form of gripping device least liable to tear or injure the fabric has a flexible plate with a rubber button which is received in a slotted metal plate, and into which the stocking is gathered and held. This form of garter fastener is in common use, and has largely superseded other types. Nevertheless it is found that the fabric of the stocking is torn in use. By the present invention I provide a very cheap and simple attachment on the stocking itself which is designed to coöperate with the above described type of garter fastener, and which absolutely prevents the fabric of the stocking being torn or injured under any circumstances. The nature of the attachment is further such as to render the engagement of the garter fastener very easily made and very secure in use, both of which are specially important requisites, as will be clearly understood by those versed in the art.

In the drawings: Figure 1 is a view illustrating the general appearance of a device embodying the principles of my invention in use; Fig. 2 is a sectional view of the attachment showing it in engaged relation with a garter fastener or supporter of the ordinary type; Fig. 3 is a side view showing the attachment or protector in its place on the stocking.

Referring to the drawings in which like parts are designated by the same reference sign, 1 indicates a stocking of the type ordi-

narily worn by ladies. To the upper edge 2 of this stocking is applied a device or attachment which constitutes the protector, and which furnishes the engaging means for the usual garter fastener or supporter. In the drawings I have illustrated this attachment 60 or supporter in the form of a flexible strip or tab 3. The most convenient practical construction comprises an ordinary piece of strong black cloth of twice the length of the finished article and folded transversely across its middle at 4. The cloth is then stitched or fastened transversely across the line 5, and around the edges of the upper part, as shown at 6, so that the upper half is a single unitary sheet or structure 7, while the lower half 70 below the line 5 has two separate divergent leaves 8. The upper part 7 of the protector has a central circular aperture 9, in which is riveted an eyelet 10. The eyelet 10 is of sufficient size to receive the usual flexible button 11, of an ordinary garter fastener or supporter (see Fig. 2).

In use it is merely necessary to place the protector on the upper edge 2 of a stocking, so that the leaves 8 fall on opposite sides thereof. The fabric is then sewed through in any way, for example, on the lines 12, running around the borders of the leaves 8. This binds the leaves and the upper edge of the stocking into a single unitary piece or sheet, and any strain which is brought on the protector in use is so distributed to the fabric of the stocking that the latter will not become injured or torn under any circumstances. The button 11 of the fastener is merely pushed through the eyelet 10 and engaged in the ordinary slotted plate 13, in the usual way.

It is evident that this attachment can be very quickly made, and is very secure and permanent in use.

While I have described the invention as made of cloth or fabric and applied to a lady's stocking, I do not desire to be limited either to this material or to this use, since the protector is capable of being made of any sheet material, and is applicable to men's and children's hose, and other garments, as well as ladies' stockings.

What I claim, is:—

As an article of manufacture, a device or attachment for ladies' stockings comprising a flexible strip of cloth 3 folded transversely

across its middle 4, and stitched or fastened transversely across the line 5 between said folded middle portion and the two ends and also along the edges 6 adjacent to the folded portion, whereby one half 7 constitutes in effect a single unitary sheet or structure, while the other half has two separable leaves 8, said half 7 being stitched around the edges

and having a central circular aperture 9, and an eyelet 10 riveted into said aperture. 10

In witness whereof, I subscribe my signature, in the presence of two witnesses.

LOUIE DUCEY.
